[57] CLAIM

The ornamental design for a wrist wallet, as shown and described.

DESCRIPTION

FIG. 1 is a top view of the wrist wallet showing my new design;

FIG. 2 is a right side elevational view thereof;

FIG. 3 is a front elevational view thereof;

FIG. 4 is a rear elevational view thereof;

FIG. 5 is a left side elevational view thereof;

FIG. 6 is a bottom view thereof;

FIG. 7 is a perspective view thereof; and,

FIG. 8 is a perspective view of the invention secured in position; the broken line showing of a hand and part of an arm is for illustrative purposes only and forms no part of the claimed design.
